UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,199,171.

Specification of Letters Patent. Patented Sept. 26, 1916.

Application filed November 13, 1915. Serial No. 61,215.

To all whom it may concern:

Be it known that I, FRANZ A. FULLER, a citizen of the United States, residing in the city of Newark, county of Essex, and State 5 of New Jersey, have invented certain new and useful Improvements in Bag-Fasteners, of which the following is a full, clear, and exact description, such as will enable others skilled in the art to which it pertains to 10 make and use the same, reference being had to the accompanying drawings, and to letters of reference thereon, forming a part of this specification.

Hitherto, in the construction of bag fasteners of the class to which my invention relates, it has been customary to provide the jaws of the ordinary forms of hand bags, pocket-books, satchels and the like, with two 15 projecting members terminating in knobs, balls or heads, which spring or snap past each other to hold the jaws together. If the hand bag or the like be unusually full, or if either the projecting members constituting the fastener, or the jaws themselves, 20 become bent or loosened, it often happens that the jaws are accidentally opened, and the contents of the bag is lost or abstracted without the knowledge of the owner. If pressure is exerted, the two frame members 25 can be pulled apart, thereby causing the knobs or heads to spring or snap past each other, thereby unlocking the bag without manipulating the fastener.

The main purpose of my invention is to 30 overcome the objections found in those fasteners heretofore employed, and to provide a pocket-book, purse or other frame, and its catch or fastener, which shall be neat in appearance, and shall be of a simple, strong 35 and durable construction, with a view of furnishing a bag or purse frame having a novel construction of spring-actuating holding catch or fastener, which can be easily manipulated.

40 All of these objects I fulfil in the preferred embodiment of my invention which I have illustrated in the accompanying drawings, to which reference is to be had, and in which similar reference characters indicate 45 corresponding parts in the several views.

In the drawings, Figure 1 represents a front elevation of one form of bag or purse frame, with a catch or fastener embodying the principles of my invention. Fig. 2 represents an end elevation of the same. Fig. 55 3 represents, on an enlarged scale, a vertical

section taken on lines *x*—*x* of Fig. 1; and Fig. 4 represents a fragmentary under plan view of the frame sections, illustrating the arrangement of the spring clip and the 60 spring for actuating the catch or fastener.

In the drawings *a* and *b* represent the usual pair of frame sections, (either channeled or angled), which are pivotally connected at their lower end portions by means 65 of suitable pins or rivets *c*, or they may be pivotally connected with each other in any other well-known manner. Inasmuch as the catch members or fasteners employed are identical in shape, a description of one will 70 suffice for both. Each of said frame sections is provided in its upper surface with a centrally-arranged, suitable opening for the reception of an extension provided on the catch member to be presently described, 75 and each frame section is further provided with a suitable nosing or projection *d*, which can be forced out from the metal from which said frame sections are made, or any other suitable means may be provided, designed to 80 be brought into holding engagement with the under side of the catch member, to firmly secure the bag frame sections or members in locked position.

The catch member, two of which are employed, may be of any desired form or configuration, and consists preferably of the chambered cap *e* formed from a single piece of suitable metal, said cap having secured to it a downwardly-projecting, spring-holding member *f*, said member having formed thereon holding means by bending the metal thereof to form a bearing or channel *g*, for the reception of the spring to be presently 90 described.

To provide a suitable finger piece or lift for the catch member, I have shown a flat piece of suitable material *h*, provided with an integral extension *i*, said extension passing through a suitable aperture in the cap 100 *e* and spring-holding member *f*, and closed down upon the under side of said member *f* in any convenient or desired manner. When the bag frame sections are closed, the nosing or projection *d* will be received 105 into the cap *e* and firmly secure the bag frame sections in locked position. In order to hold said catch members in their normal initial positions, I provide each one with a suitable torsion spring *j*, one end of which 110 is passed through the bearing *g* of the spring-holding member, and rests against

the under side of the frame section, and the other end of which is secured to the spring clip *k*. This spring clip *k* in its preferred form, or when used in connection 5 with a frame member of channeled cross-section, consists of a single piece of suitable material, channeled, and of a dimension and shape approximating that of the channeled frame section to which it is se-
10 cured by being forced therein. This spring clip is provided with a centrally-arranged, depressed portion *l*, said portion being fur-
ther provided with openings *m* through
15 which one end of the spring passes, in
which it is firmly held and prevented from
rotation or accidental displacement. When
the spring has in this manner, been ar-
ranged in position and secured to the spring
20 clip and catch member, it, together, with
the spring-holding means on the catch mem-
ber, will limit the oscillatory movement of
said catch member. In this manner, the
movable catch will be retained in proper
locked or holding position. When the catch
25 member is raised, the projection *d* will be-
come disengaged from the interior of the
cap *e*, thereby placing the spring *j* under
sufficient tension that when the operator re-
leases the hand from the catch, the spring
30 will again cause the catch member to return
to its normal position. The holding or
locking operation of the catch member thus
operatively connected with the frame sec-
35 tion, is caused by snapping or forcing the
edge of the cap *e* over the usual projection
d upon the frame member, in the well-
known manner. When it is desired to open
40 the bag, it is merely necessary to apply
thumb and finger pressure in opposite di-
rections to the finger pieces *h* to snap the
caps *e* over the projections *d*, said pressure
tending both to move the fasteners oppo-
45 sitely out of locking engagement with the
frame sections and the frame sections away
from each other. This opening operation is
readily accomplished with one hand, and
without any particular effort.

Experience has demonstrated that the organization above described is a practical and efficient one for accomplishing the ends

sought by this invention. The construction may, however, be varied in detail by those skilled in such matters, without departing from the invention.

I desire to claim the invention as broadly 55 as the state of the art will permit, and with no limitations other than such as may be expressed in the claims, as they may be allowed.

Having thus described my invention, 60 what I desire to claim is:—

1. In fastenings of the class described, a pair of pivotally connected bag frame members, each member provided with a pivotally-connected and spring-actuated, disengaged fastener, adapted for receiving from the thumb and finger pressure tending both to move the fasteners oppositely out of locking engagement with the frame sections and the frame sections away from each 70 other.

2. In combination with a pair of frame members, a catch member mounted upon each of said frame members and having interlocking engagement with the other frame 75 member, and a spring for each catch member, one end of which is secured to the catch member and the other end of which is secured to the frame.

3. In combination with a pair of frame 80 members, a pivotally connected, spring-actuated catch member mounted upon each of said frame members, disengaged from each other, and having locking engagement with the opposite frame member, adapted 85 for receiving from the thumb and finger pressure tending both to move the catch members oppositely out of locking engagement with the frame sections and the frame sections away from each other and a spring 90 for each catch member, one end of which is secured to the catch member and the other end of which is secured to the frame.

This specification signed and witnessed
this 11th day of November, 1915.

FRANZ A. FULLER.
